HAT PROTECTING CASE

Duane D. Cline, 7152 Fenway Drive, Westminster, Calif.

Filed July 30, 1965, Ser. No. 86,374

Term of patent 14 years

(Cl. D58—12)

I claim:

The ornamental design for a hat protecting case, substantially as shown.
